UNITED STATES PATENT OFFICE.

MILTON H. BALLARD, OF BEVERLY, MASSACHUSETTS, ASSIGNOR TO UNITED SHOE MACHINERY CORPORATION, OF PATERSON, NEW JERSEY, A CORPORATION OF NEW JERSEY.

SKIVING MACHINE.

Application filed October 3, 1925. Serial No. 60,352.

This invention relates to skiving machines and is herein illustrated as embodied in a machine of the Amazeen type.

In machines of this type the work is fed to a rotary disk knife by a feed roll, the angle of the scarf produced being varied by varying the relative angular positions of the knife and roll. Either the knife or the roll may be angularly adjustable. In machines in which the roll is angularly adjustable, it is desirable, in order to facilitate the rapid adjustment of the machine, for producing different types of scarfs, that the axis about which the roll is adjustable should pass through an element of the roll adjacent to the knife (or through said element extended) and that provision should be made for adjustment of the roll relative to said axis so as to locate the roll in various positions with respect to said axis.

According to one feature of the invention, the feed roll is mounted in a carrier which is angularly adjustable about an axis passing through the element referred to above, means being provided for relative bodily adjustment between the roll and its carrier so that the inner corner of the roll which is adjacent to the knife may be positioned in the axis or on either side of the axis as may be desired. In the illustrative construction the carrier is angularly adjustable about an axis which is substantially at right angles to and passes through an element or extended element of the roll adjacent to the knife, said roll being adjustable with respect to the carrier in a direction at right angles to said axis so as to locate the inner corner of the roll in the various positions which have been referred to above. With this construction, as will be explained in detail below, the production of two different given scarfs upon different portions of the same piece of work, and the change in adjustment so as to adapt the machine to produce two scarfs different from the first two upon another piece of work, are greatly facilitated.

It is desirable in machines of this kind that provision be made for grinding the knife of frequent intervals. According to another feature of the invention, an improved mounting for a grinder is provided by which the grinder is readily adjustable toward and from the knife and is compelled

to run freely and true in any position to which it may be adjusted. In the illustrated construction, the grinder is fast to the projecting end of a conical head which extends through a conical bearing, the pulley by which the grinder is driven being arranged to surround the conical bearing.

These and other features of the invention, including certain details of construction and combinations of parts, will be described as embodied in an illustrative machine and pointed out in the appended claims.

Referring now to the accompanying drawings:

Figure 1 is a side elevation of a machine in which the present invention is embodied;

Figures 2 and 3 show two angular positions of the roll with the inner corner of the roll located inside the axis about which the roll is angularly adjustable;

Figures 4 and 5 show two angular positions of the roll with the inner corner of the roll located outside the same axis, a wider roll being shown than that of Figures 2 and 3;

Figure 6 shows a roll with its inner corner located in said axis;

Figure 7 is a plan of the machine;

Figure 8 is a front elevation of the machine;

Figures 9 and 10 are, respectively, a sectional and a perspective view showing the construction and mounting of the knife grinder; and

Figures 11 and 12 are, respectively, a front and an end elevation of the presser foot and its mounting.

Referring first to Figures 2 to 6, the mounting of the knife and roll and certain adjustments which can be made will be explained. The knife 11 is of the rotary disk type and is adjustable toward and from the roll 13 and horizontally in the plane of the drawing. The roll is mounted in a carrier which is angularly adjustable about an axis substantially perpendicular to and tangential to an element of the roll (or said element extended) which is adjacent to the knife, said axis being fixed and passing through the point x . The work 100 is fed by the roll (and a cooperating disk presently to be described) away from the observer in the direction of extent of the axis which passes

through the point α . The carrier in which the roll is mounted is adjustable angularly about the axis which passes through the point α into two positions, which may be determined by two adjustable stops, as will presently appear. When, therefore, it is desired to produce two scarfs of different character upon two portions of a piece of stock, the roll, the knife and the stops are so adjusted that the roll and knife are normally in position to produce one of the scarfs, and depression of a treadle will tilt the roll into position to cause the other one of the scarfs to be produced.

For example, on a bal upper it is desirable to produce a feather-edge scarf along the lower margin where said margin is to extend beneath and be sewed to the upper margin of the vamp; and to produce a shoulder scarf along the front margin of such upper where said margin is to be folded to make a finished edge which will be visible in the finished shoe. Figures 2 and 3 show the roll and knife in positions to produce these two scarfs. The roll is normally in the position shown in Figure 2 for the production of the feather-edge scarf. When the treadle is depressed, the roll is rotated in a clockwise direction into the position shown in Figure 3 for the production of the fold or shoulder scarf. It should be noted that in these two positions of the roll, the upper inner (right-hand) corner of the roll is inside (to the right of) the axis which passes through the point α .

In the position of parts shown in Figures 4 and 5, the inner upper corner of the roll is outside (to the left of) the axis which passes through the point α , this position having been attained by adjusting the roll outwardly (to the left) in its angularly adjustable carrier. And, in order that the knife may occupy the proper position with respect to the roll, it has been adjusted to the left. The two positions shown in Figures 4 and 5 are suitable for skiving cut-off vamps. The position in Figure 4 is adapted to produce across the rear ends of the legs of the vamps two so-called seam scarfs, such scarfs as shown being short and abrupt. The position in Figure 5, caused by rotating the roll in a clockwise direction, is adapted to produce a long feather-edge scarf across the toe portion of the vamp. It will be understood that the machine is supplied with removable and replaceable rolls of different widths, the roll shown in Figures 4 and 5 being wider than that shown in the other figures so as to provide for the production of the long scarf shown in Figure 5. In Figure 6 the parts have been so adjusted that the inner upper corner of the roll is located in the axis which passes through the point α , such adjustment being adapted particularly for the production of scarfs which differ only in inclination

and not in the thicknesses of their edges.

Referring now more particularly to Figure 8, the mountings of the roll and knife will be described. The work is fed away from the observer to the knife 11 by the feed roll 13 and a cooperating feed disk 15. The feed roll shaft extends through a bore in a block 16, which is horizontally slidable on an angularly adjustable carrier 17, the right-hand end of the roll shaft extending into a cup 19 which is connected by a ball-and-socket joint with one member 21 of a telescopic shaft, the other member 23 of which is connected by a ball-and-socket joint with the hub of a pulley 25. The right-hand end of the roll shaft is held in the cup 19 by a set-screw 27 so that the roll and roll shaft may readily be removed and replaced, when, for example, it is desirable to use a wider or a narrower roll or one of a different shape. The block 16, by which the roll shaft is carried, is held in adjusted position in the carrier 17 by a clamp operated by a thumb-screw 29. When the thumb-screw is loosened, the block 16, and with it the roll, may be adjusted to the right or the left in order to position the upper inner corner of the roll with respect to the axis about which the roll carrier 17 is angularly adjustable in the manner which has been referred to in connection with Figures 2 to 6. A scale 31 on the block 16 facilitates such adjustment.

The carrier 17 is slidable on two stationary curved guides 35 (Fig. 1) and held on these curved guides by curved gibbs 37. The curve upon which the guides 35 are formed is struck about an axis (see point α of Figures 2 to 6) substantially perpendicular to and tangential to an element of the roll (or said element extended) which is adjacent to the knife, said axis being thus tangential to the periphery of the roll (or to the periphery extended). In order to provide means for tilting the carrier, by sliding it on the curved guides 35, a rod 39 is pivoted at its outer end at 41 to the carrier 17, and at its inner end extends up through a bore in a pin having a square head 43. The pin is carried by spaced upright parts 45 of one arm of a bell-crank lever, the other arm 47 being pivoted to the upper end of a treadle rod 49. Stops 51, threaded on a stationary rod 52 and held in adjusted position by set screws 53, limit the movement of the square head 43 in either direction. A spring (not shown) urges the treadle rod 49 downwardly at all times and normally holds the square head 43 against the right-hand stop 51 and the roll in its initial position,—that is in a position such as shown in Figures 2 and 4. When the treadle rod is pushed up by manipulation of a treadle (not shown), the square head moves into contact with the left-hand stop 51, and the roll is swung clockwise into

its second position,—that is into a position such as that shown in Figure 3 or 5. In the usual operation of the machine the roll is caused to occupy one or the other of these 5 two positions; but, of course, the operator may at any time hold the roll in any intermediate position. A scale 55 on one of the gibs 37 and a pointer 57 on the carrier 17 indicate to the operator the angular position 10 of the roll.

It is desirable that the presser foot 59 and edge gage 61 should be mounted for adjustment with the feed roll, and to this end they are mounted upon a bracket 63 which is 15 pivoted about a horizontal pin 65 carried by a lug on the block 16. The bracket 63 is normally held in the position shown by a spring catch (not shown) but may be swung down at any time about the pivot 65 when 20 the spring catch is released, to permit removal and replacement of parts. The gage 61 is fast to the left-hand end of a bar 67 slidable horizontally in a dove-tailed guide-way formed in the bracket 63 and is held 25 in adjusted position by a clamp 69. The presser-foot 59 is fast to the left-hand end of a bar 71, which has at its right-hand end a curved portion extending freely around a pin 73 carried by lugs extending up from the 30 bar 67, the right-hand extremity of the bar 71 being rounded and extending down into a rounded socket formed in the bar 67. The right-hand end portion of the bar 71 is held 35 against the inner face of a lug 72 on the bar 67 through the pin 73. To this end (see Figure 12) the pin 73 is held from moving to the right by a cotter pin 74 and has at its right-hand end a head between which and the right-hand side face of the bar 71 is a 40 spring 76 and a washer 78. By this construction the bar 71 which carries the presser foot is prevented from swinging about its longitudinal axis and at the same time may be readily removed and replaced. As a further 45 means for preventing swinging or twisting of the bar 71 about its longitudinal axis, a square pin 80, rigid with the edge gage, passes up through a rectangular hole in the bar 71 and in the stem of the presser foot 59. The right-hand vertical face of the 50 presser-foot 59 should lie close to the adjacent vertical face on the edge gage in all positions of the presser-foot so as to prevent the edge of the leather from working 55 up between these two members. The present construction is designed with this end in view. The bar 71, it will be noted, is in effect pivoted about the axis of curvature of the rounded socket 75, said axis being located 60 at a considerable distance from the presser-foot, and just slightly above the operative face of said foot. The movement of the presser-foot within the limits encountered in 65 upper leather is so nearly vertical, due to the distance from the foot to the rounded socket

75, that there is practically no opening up of the space between its right-hand face and the adjacent face of the edge gage. At the same time, the foot is freely movable up and down by reason of the location of the 70 axis of the rounded socket 75 slightly above the lower face of the foot. A screw 77 threaded into the gage bar 67 has beneath its head a coiled spring which holds the presser bar 71 down yieldingly; and a stop 75 screw 79 limits the downward movement of the presser bar.

The feed disk 15 (Fig. 8) is carried by the same angularly adjustable carrier 17 as is the feed roll so that the feed disk and the 80 feed roll maintain their cooperative relation in any position to which the carrier 17 is adjusted. To this end an upwardly extending arm on the block 16, which, as has been explained, is mounted on the bracket 17, has 85 a split boss 81 to hold an elongated bearing 83 for a shaft 84. At its left-hand end this shaft carries a spiral gear 85 (Fig. 1) which meshes with a spiral gear 86 on the shaft 87 of the feed disk, said shaft being mounted in vertically alined bearings in a member 89 which is rigid with the bearing 83. The bearing 83 is adjustably held in place in the split boss 81 by a pinch screw 91 whereby the feed disk may be adjusted in a path 90 parallel to the axis of the feed roll. A coiled spring 92 (Fig. 1) extends down into a socket in the shaft 87 of the feed disk, a thumb-screw 93 being provided for varying the tension of the spring. The horizontal 95 shaft 84 is connected at its right-hand end by a ball-and-socket joint with one portion 95 of a telescopic shaft, the other portion 97 of which is connected by another ball-and-socket joint with a short shaft 99 to which is 100 fast a small pulley 101. With the above construction, it will be apparent that the feed disk partakes of the angular adjustments of the feed roll and may be adjusted with respect to the roll in a path parallel to 105 the axis of said roll.

Referring now more particularly to Figure 7, the feed roll 13 is driven by a belt 103 which passes around the pulley 25 and around one step 105 of a pulley which is 110 fast to a countershaft 107, a belt-tightener pulley 109 being provided for maintaining the belt 103 taut. If it is desired to increase the speed of rotation of the feed roll, the belt 103 is shifted to the larger step 111 of 115 the driving pulley. The countershaft 107 is driven by a belt 113 which passes around a pulley 115 on said countershaft and around a smaller pulley 117 on the driving shaft 119, said driving shaft carrying the usual 120 fast and loose pulleys 121, 123 from one to the other of which the driving belt 125 may be shifted by manipulating a belt shifter 127. The feed disk shaft, which carries at 125 one end the small pulley 101, is driven from 130

the countershaft 107 by a belt 108 which passes around said pulley, around a pulley 129, on the countershaft 107, around an idle pulley 131, located below the pulley 101; back around a pulley 132 also on the countershaft 107 and back to the pulley 101. It will be noted from an inspection of the sizes of the various pulleys in Fig. 7 that the feed disk is rotated at a faster rate than is the feed roll. The long belt 108 with its double run is, however, maintained fairly loose, so that it will slip if at any time the operator holds back on the work as it is passing between the feed roll and feed disk, such holding back being desirable when sharply curved edges, such for example as throats of vamps, are encountered.

The knife 11 is driven by a belt 135 (Fig. 1) which passes around a large pulley 137 fast to the drive shaft 119 and around a small pulley 139 fast to the knife shaft, a tightener pulley 141 being provided for this belt. The knife, it will be understood, may be adjusted toward and from the feed roll as is usual in machines of this general type by manipulating an adjusting screw 143. The knife (Fig. 8) may also be adjusted horizontally in a direction substantially parallel to the feed roll shaft and, to this end, is carried in a bracket 145 having a horizontal tongue which is received in a suitably shaped horizontal groove or guideway 147 in the frame of the machine. The bracket has in it a horizontal slot 149 through which extends a clamping screw which is threaded into the frame of the machine, a handle 151 being provided for convenient manipulation of the clamping screw. As shown in Figure 7, a scale on the frame of the machine and a mark on the knife-carrying bracket 145 are provided for the convenience of the operator.

The grinder bracket 153 is rigid with the bracket which carries the knife and is therefore adjusted when the knife bracket is adjusted. Referring now more particularly to Figures 9 and 10, the mounting of the grinder will be described. Slidable in a bore in the bracket 153 is a sleeve 155, and mounted in this sleeve is a short shaft 157. The lower end of this shaft has a conical head which fits in a conical bearing 159 carried by the sleeve. The upper end of the shaft 157 has a conical socket to receive the conical end of a small screw 161 which is threaded into the upper end of the sleeve 155 and holds the conical head at the lower end of the shaft in its conical bearing. A lock-nut 163 holds the screw 161 in adjusted position. The grinder 165 has a conical bore in its center to receive the lower portion of the conical head of the shaft 157, and is fastened to said conical head by a screw 167. A belt 169 (shown best in Figures 1 and 7) passes around a pulley formed on the grind-

er, under a tightener pulley 171 and around a pulley 173 which is loose on the driving shaft 119 and adapted, as will presently be described, to be connected frictionally with the constantly rotating pulley 137 when desired.

Referring again to Figures 9 and 10, as well as to Figure 1, the grinder is urged downwardly at all times toward the knife by a spring 175 which is coiled about a stud 177 carried by the bracket 153 and has one end extending into a slot in the sleeve 155 and the other end resting against a part of the bracket, said spring tending at all times to urge the grinder toward the knife. In order to permit the operator to control the downward movement of the grinder, a lever 179, pivoted about the stud 177, has one end bearing against the upper wall of a slot in the sleeve 155 and the other end engaged by a screw 181 so that, by turning the screw in one direction or the other, the grinder may be moved from operative to inoperative position, or vice versa.

Referring now to Figure 7, it has been explained that the pulley 173, which drives the grinder, may be clutched frictionally to the pulley 137 when desired. To this end, the pulley 173 is slidable as well as rotatable on the shaft 19, and there is located between it and the pulley 137, a fibre disk 183. In order to provide means for pushing the pulley 173 toward the pulley 137, when desired, a rod 185 (Fig. 1), slidably mounted in the frame of the machine and located directly beneath the driving shaft 119, carries at that end which is adjacent to the pulley 173 a fork in the arms of which are mounted small rollers 187 (Fig. 7). The other end of the rod 185 is engaged by one arm 189 of a bell-crank lever which is pivoted to the frame of the machine at 191. The other arm 193 of the bell-crank lever is pivoted to one end of a rod 195 the other end of which extends to the front of the machine and has a head 197. When the rod is pulled to the right, as viewed in Figure 7, the small rolls 187 engage the pulley 173 and push it toward the pulley 137 so as to cause the pulley 173 to be rotated by the pulley 137 and rotation thus imparted to the grinder 165.

Referring again to Figure 9, it will be noted that the plane of the belt 169 where it passes around the grinder pulley is located about midway between the upper and lower ends of the conical bearing member 159, and that the taper of the conical bearing member and of the head of the grinder shaft 157 is gradual. When the grinder is rotated by the belt there is a slight tendency for the conical head to rise so that the grinder turns freely. The screw 161 is so adjusted, however, that the extent of the rise is very small. The grinder shaft thus rotates freely with its lower end in the bearing 159 and its up-

per end engaged by the pointed screw 161. It will also be noted that, when the adjusting screw 181 is manipulated to raise or lower the grinder, the sleeve 155 is raised or lowered so that the relation of the grinder shaft 157 to its bearings and the relation of the belt 169 to the conical bearing 159 remain unchanged; and the grinder shaft runs as freely in one position as in another.

16 As the knife wears away due to being ground, it is desirable to provide for adjustment of the roll toward the knife in the direction of feed movement of the work. To this end, the angularly adjustable carrier 17, 15 the gibs 37 and the pulley 25 are mounted on a bracket 202 which may be swung about a pivot 204 by manipulating a thumb screw 206, the bracket being adapted to be clamped in adjusted position by turning a 20 hand lever 208.

Having thus described my invention, what I claim as new and desire to secure by Letters Patent of the United States is:—

1. A machine of the class described having, in combination, a skiving knife, a feed roll, a carrier by which the feed roll is supported, said carrier being angularly adjustable about an axis which is substantially perpendicular to an element, extended or otherwise, of the roll, and means whereby relative bodily adjustment between the roll and the carrier may be effected to position the inner corner of the roll in the axis or on either side of the axis as may be desired.

35 2. A machine of the class described having, in combination, a skiving knife, a feed roll, a carrier by which the feed roll is supported, said carrier being angularly adjustable about an axis which is substantially perpendicular to an element, extended or otherwise, of the roll, and means for adjusting the roll with respect to the carrier to position the inner corner of the roll in the axis or on either side of the axis as may be desired.

45 3. A machine of the class described having, in combination, a skiving knife, a feed roll, a carrier by which the feed roll is supported and with respect to which the roll is adjustable, a presser foot, an edge gage, and 50 connections between the feed roll and the foot and gage such that the foot and gage are adjusted in unison with the feed roll when said roll is adjusted with respect to the carrier.

55 4. A machine of the class described having, in combination, a skiving knife, a feed roll, an angularly adjustable carrier by which the feed roll is supported and with respect to which the roll is adjustable, a 60 presser foot, an edge gage, and connections between the feed roll and the foot and gage such that the foot and gage are adjusted in unison with the feed roll when said roll is adjusted with respect to the carrier.

65 5. A machine of the class described hav-

ing, in combination, a skiving knife, a feed roll, a block in which the feed roll is rotatably mounted, a carrier in which the block is adjustable, said carrier being angularly adjustable about an axis which is substantially perpendicular to an element, extended or otherwise, of the feed roll, and a presser foot and edge gage mounted on the block.

6. A machine of the class described having, in combination, a skiving knife, a feed 75 roll, a feed disk cooperating with the roll to advance the work to the knife, and means for rotating the feed disk comprising four pulleys arranged in pairs and a double-run belt passing loosely around said pulleys.

7. A machine of the class described having, in combination, a skiving knife, a feed roll angularly adjustable to vary the inclination of the scarf produced by the knife, a feed disk cooperating with the roll and 85 angularly adjustable with it, and means for driving the knife roll and disk, the means for driving the disk comprising a universal joint and a telescopic shaft to permit adjustment of the disk with the roll.

8. A machine of the class described having, in combination, a skiving knife, a feed roll, an angularly adjustable carrier by which the feed roll is supported, a feed disk 95 cooperating with the roll and also supported by the carrier, and means including universal joints for rotating the roll and the disk so as to permit the carrier to be adjusted while maintaining the rotation of the roll and disk and to permit the disk to 100 be adjusted with respect to the roll.

9. A machine of the class described having, in combination, a skiving knife, a grinder for said knife, a rotatable shaft on which the grinder is mounted, said shaft 105 having a conical portion, a conical bearing to receive said portion, a pulley rigid with the grinder and surrounding the conical bearing, and a driving belt passing around the pulley.

10. A machine of the class described having, in combination, a skiving knife, a grinder for said knife, a rotatable shaft having a conical head at one end, a conical bearing through which said head projects, 115 means for fastening the grinder to the projecting portion of said head, and means engaging the shaft to hold the head in the bearing.

11. A machine of the class described having, in combination, a skiving knife, a grinder for said knife, a rotatable shaft having a conical head at one end, a conical bearing through which said head projects, 120 means for fastening the grinder to the projecting portion of said head, and a conical screw engaging a socket in the shaft to hold the head in the bearing.

12. A machine of the class described having, in combination, a skiving knife, a 130

- grinder for said knife, a rotatable shaft having a conical head at one end, a conical bearing through which said head projects, means for fastening the grinder to the projecting portion of said head, means for holding the head in the bearing, a driving member rigid with the grinder and surrounding said bearing, and means for rotating said member.
- 10 13. A machine of the class described having, in combination, a skiving knife, a bracket adjustable on the frame of the machine in which the knife is mounted, a support rigid with said bracket and having a 15 conical bearing, a grinder shaft having a conical portion near one end received in said bearing, a grinder for the knife fast to said conical portion, and an adjusting screw engaging the end of the shaft which 20 is remote from the bearing.
14. A machine of the class described having in combination a skiving knife, a feed roll, a feed roll shaft, a carrier angularly adjustable about an axis which is substantially perpendicular to an element, extended or otherwise, of the roll, and a block in 25 which the feed roll shaft is rotatably mounted, said block being slidably adjustable on the carrier in a path parallel to the feed
- roll shaft and means for holding said block 30 in adjusted position.
15. A machine of the class described having in combination a skiving knife, a feed roll, a feed roll shaft, a carrier angularly adjustable about an axis which is substantially perpendicular to an element, extended or otherwise, of the roll, and a block 35 in which the feed roll shaft is rotatably mounted, said block being slidably adjustable on the carrier to position the inner corner of the roll in the axis or on either side of the axis as may be desired, and means for holding said block in adjusted position.
16. A machine of the class described having, in combination a rotary disk skiving knife, a feed roll for advancing work to the knife, two curved guideways, the center of which lies in an axis which is tangential to an element of the roll at a point spaced 40 from the inner end thereof, a roll carrier having curved guides located in said guideways, means for rotating the roll, and means for adjusting the roll carrier angularly 45 while maintaining its rotation.
- 50 In testimony whereof I have signed my name to this specification.
- 55 MILTON H. BALLARD.
